CLAIM

The ornamental design for a holder of opening and closing device for the seat or the seat lid of a toilet bowl, as shown and described.

DESCRIPTION

FIG. 1 is a side elevational view of a holder for an opening and closing device for the seat or the seat lid of a toilet bowl; FIG. 2 is a top plan view thereof;

FIG. 3 is a bottom plan view thereof;

FIG. 4 is a side elevational view thereof, the opposite side being an identical mirror image of FIG. 4;

FIG. 5 is a front, top, side perspective view thereof;

FIG. 6 is a sectional view taken along line 6—6 of FIG. 1, submitted to help show the contour of the present design;

FIG. 7 is a sectional view taken along line 7—7 of FIG. 4, again to show the contours of the present design; and, FIG. 8 is a sectional view taken along line 8—8 of FIG. 1 to help show the contours of the present design.
